UNITED STATES PATENT OFFICE

2,494,918

INDUCTIVELY ENERGIZED ELECTRO-DYNAMIC LOUD-SPEAKER

Walter K. Volkers, Schenectady, N. Y., assignor to Volkers & Schaffer, Inc., a corporation of New York

Application September 17, 1946, Serial No. 697,588

1 Claim. (Cl. 179—115.5)

1

The present invention covers a new type of dynamic loudspeaker which has a stationary voice coil instead of the moving voice coil, which is being customarily used in dynamic speakers today. The principal advantages of a stationary voice coil when compared to a moving voice coil are the following:

1. Since the weight of the coil is not attached to the speaker's cone and therefore does not influence its resonant frequency, more wire volume and wire weight can be used for the construction of the voice coil. This increases its efficiency, i. e. the over-all electro-magnetic-mechanical performance of the speaker.

2. Due to the increased permissible weight and volume of the voice coil its impedance can be matched directly with the output tubes, whereby the output transformers, now customarily used, can be omitted. This greatly reduces the manufacturing costs of sound amplifiers, radio receivers and similar electronic equipment using the new type of loud speaker.

3. Stationary voice coils are less delicate and require less skill in manufacturing than moving coils and therefore reduce the amount of labor required for producing the new speaker.

4. The total weight of the active parts attached to the speaker cone is smaller in case of the new design as compared with an ordinary moving coil speaker, giving the new speaker improved frequency response and better sensitivity.

5. A stationary voice coil permits the elimination of the pig-tail connections to the voice coil.

While the structures to be described herein are especially useful for loud speaker purposes, they have other uses as will be explained more fully hereinafter. Broadly, my invention is useful in the field of electro-mechanical transducers for translating mechanical vibrations into electrical vibrations or, conversely, translating electrical vibrations into mechanical vibrations. My improved transducer involves a vibratory armature formed of thin sheet-like magnetic material mounted for vibration in its own plane and includes a magnetic system (either permanent magnet or electro-magnetic) for establishing an exciting magnetic field through the armature normal to the plane thereof, and a coil arranged in inductive relation to the armature with the turns thereof at right angles to both the direction of vibration of the armature and the direction of the biasing field. When the coil is energized by a signal current, the interaction between the field of the coil and the exciting field establishes mechanical forces on the armature to move

2

or vibrate the same in accordance with the well known three-finger rule in determining electrodynamic action. Conversely, if the armature is vibrated, corresponding voltages are induced in the coil.

My invention is illustrated and compared to previous standard designs in the accompanying drawing in which

Figure 1 shows a cross-section of the electromagnetic driving system of an ordinary moving-coil type speaker; and

Figure 2 is a cross-section of the new stationary-coil type speaker.

The conventional dynamic loudspeaker shown in Figure 1 has a moving coil 1 wound on a cardboard cylinder 2 which is fastened to the speaker's cone 3. The magnetic system for supplying the exciting field consists of a soft iron core 4, a ring-type permanent magnet 5, a yoke plate 6 and a pole-ring 7. The magnetic lines of force which penetrate radially the active air gap between the core 4 and the pole-ring 7 are illustrated by the arrows 8 and 9. Electrodynamical action between the flux produced by current passing through the wires of coil 1 and the magnetic lines of force 8 and 9 creates a mechanical upward or downward pulling action as indicated by arrows 10 and 11. This force causes the moving coil 1 to move up and down which makes the speaker cone 3 vibrate and produce sound.

The preferred form of new speaker according to the present invention is shown in Figure 2. It also has a paper cone 21 which produces sound. However, instead of a moving coil, there are attached to the cone two concentric rings 22 and 23 which are made of soft iron, preferably low-loss sheet material. They are held in spaced relation by a lightweight ring 24 made of cardboard, wood or some plastic material. Between the two rings 22 and 23 there is placed the voice coil 25 which is stationary and can, therefore, be attached to any stationary part of the loudspeaker, for instance, its iron core 26. A supporting ring 27 made of plastic material such as phenolic resin or any equivalent insulation material may be used for this purpose. The other parts of the loudspeaker closely resemble those of the standard speaker shown in Figure 1. Again a permanent ring-type magnet 28 is being used, also a yoke disc 29 and a pole ring 30. The magnetic lines of force forming the exciting field are again radial as illustrated by arrows 31 and 32 and again they produce mechanical raising or lowering forces as indicated by arrows 33 and 34. In this case, however, there are no direct active

magnetic forces between the stationary magnetic parts represented by the core 26 and the pole ring 31 and the moving parts represented by the two thin iron rings 22 and 23 which are attached to the loudspeaker. Instead, the actual internal dynamic action takes place between the stationary coil and the thin iron parts emitting and absorbing the flux surrounding it. In other words, the actual driving effect is caused by the stationary coil 25 and the two thin iron rings 22 and 23. Since the flux passes through them only transversely, they can be made extremely thin and light.

From the foregoing description it will be seen that in my invention the vibratory armature is formed of relatively thin sheet-like magnetic material mounted for vibration in its own plane. While the armatures 22 and 23 described above are of cylindrical form, it will be understood that they may assume other forms such as a flat vane. It will also be noted that the exciting field established by magnet 28 passes through the magnetic armature normal to the plane thereof, and the turns of the coil 25 are arranged at right angles to both the direction of the exciting field and the direction of vibration of the armature.

It goes without saying that the present invention is not limited to the permanent-magnet-type speaker shown in the drawings for producing the exciting field. It can be applied to speakers having any other type of magnetic excitation. A simple bar-type magnet can be used instead of the ring magnet or any other magnet exciting device may be used. Bell-shaped, horseshoe-type, laminated types, and many other forms of permanent magnets can be used, also electromagnetic excitation by means of exciting coils. To show all possible types of speakers incorporating my invention would exceed the available space for drawings accompanying this patent specification.

Like the ordinary dynamic loud speaker, my invention is capable of being used for translation of acoustic vibrations, or mechanical vibrations, into corresponding electric currents. For example, structures involving the principles outlined above may be used as microphones, phonograph pickup elements and recording heads. Also, while I have described my invention as applied especially to loudspeakers, it is obvious that the same type of structure may be used in telephone receivers of the head-set type and bone-conduction type.

I claim:

An electro-mechanical transducer comprising, in combination, a magnetic structure including an annular pole piece surrounding a central core and providing an annular air gap surrounding said core and including means for establishing a radial exciting field in said gap, an annular coil mounted in fixed position within said air gap and in spaced relation with both gap-forming members to provide concentric component air gaps of annular form on radially opposite sides of said coil, and a vibratory armature comprising a pair of concentric magnetic cylindrical members positioned within said component air gaps and mounted for vibration parallel with the axis of said coil.
